UNITED STATES PATENT OFFICE.

OTTO BARTEL, OF NEW YORK, N. Y.

TORCH.

991,191.

Specification of Letters Patent.

Patented May 2, 1911.

Application filed February 25, 1910. Serial No. 545,634.

To all whom it may concern:

Be it known that I, Otto BARTEL, a citizen of the United States, residing at New York, in the county of New York and State of New York, have invented new and useful Improvements in Torches, of which the following is a specification.

The object of my invention is a construction of a simple automatic torch which can be made at a small cost and which will burn alcohol and other inflammable fluids as fuel.

In the accompanying drawing Figure 1 is a front view of the torch. Fig. 2 is a sectional view of same. Fig. 3 is another sectional view of a modified construction in which the torch is shown inverted. Fig. 4 is a plan view of Fig. 1.

The frame or tank of the torch is made of preferably metal as indicated at *a*. The bottom of the tank is preferably slanted as indicated at *b*.

c and *c'* are openings in the tank for the purpose of filling and for letting the material out. These openings *c* and *c'* are preferably threaded and the opening *c* is closed by a threaded plug *e* corresponding to the thread in the opening *c* and a washer is interposed between the wall of the tank *a* and the plug *e* so as to allow the plug *e* to fit tightly into the tank *a*. The outlet *c'* is also threaded and into this opening *c'* the burner tube *f* is threaded as shown in Fig. 2. If desired, the opening *c* and the plug *e* shown in the drawing may be dispensed with and the rear wall of the tank made solid and the tank may be filled through the outlet opening *c'* which is the same opening holding the burner tube *f*.

The washer *l* is interposed between the frame *a* and the collar *m* on the burner tube *f*. This collar *m* may be provided with a wing or flange *n* to facilitate the operation of screwing the tube *f* into the tank *a*. The shoulder *k* made of non-heat conducting material may also be placed on the tube *f* between the collar and the outer tube *i*. The fluid to be used, is placed in the tank *a* and is taken up by packing *h* which may be an ordinary wick or a non-absorbing metal wick such as steel shavings or asbestos or it may be of clay or any suitable material which will allow the fluid or gas from the tank *a* to pass toward the opening *f'*. This wick or packing is placed in the burner tube *f*. If an ordinary wick is used it may be

cut flush with the burner tube *f* as shown in Figs. 2 and 3 or it may be long and project into the tank as in the case of an ordinary lamp wick.

At the end of the burner tube *f* is a small metal plug *g* having an opening extending its entire length terminating at opening *f'*, or the plug may be made solid and smaller than the inside of the tube to allow the gases to pass by it. Over the burner tube *f* is placed an outer tube *i* made of metal or stone or earthenware or any suitable material and fitting closely over burner tube *f*; preferably this tube *i* is made of metal and has a larger inside diameter extending beyond the inner burner tube *f*. I do not wish to be confined however to having the burner tubes *f* and *i* made separately. They may, if desired be made in one piece as shown in Fig. 3. The handle may be secured to any part of the tank, the tank being formed to have several bases as supports, so that when not in operating position, either of the bases may be used as a support, so that the fluid will not be in contact with the opening in burner.

The operation of the device is as follows: The tank *a* is filled or partly filled with an inflammable fluid preferably alcohol. The fluid is taken up by the packing *h* and if a metal wick or nonabsorbing wick is used, the fluid penetrates between these parts until it reaches part *g*. Part *g* prevents, in case an ordinary wick is used, any portion of the wick stopping up or plugging up the hole *f'* and this plug *g* also helps to produce a greater amount of gas when inner tube *f* is heated. If a flame is now applied to outer tube *i* the outer tube *i* and the inner tube *f* will immediately warm up and after reaching a certain temperature will cause the fluid in the inner tube *f* to change into gas and if the flame is then moved toward the opening of outer tube *i* the gas will ignite. As these gases will develop in a larger degree than the size of the opening *f'* will allow them to escape, a certain amount of force is produced by which these gases escape from opening *f'* and being ignited, will keep the outer tube *i* continually heated and thus continue to create new gases. The outlet opening in the tank being below the top line of the fluid, the fluid thus acts as a valve for the tube *f* in which the gases are created and the position of this outlet opening secures

a more uniform feed of the wick or packing than could be obtained if the outlet opening were above the top fluid line and the fluid was carried upward by means of an absorbing wick toward the outlet opening *c*'. During the process of operating this torch the fluid in the tank will gradually grow warmer and also develop gases and as the opening *f*' controls or checks the escape of these gases the force of the flame will gradually grow stronger and the inside of the tank not filled with fluid will contain compressed gases. The size of the burner tubes will determine the amount of gas which will develop. Should more gas develop than can be burned by the flame, this gas will blow out the flame and the flame being out, no more heat will be created and consequently the development of gas will cease. If the operator extinguishes the flame, there is for a short period some gas developed which would press the fluid into the wick and as it cannot be consumed at the outlet when there is no flame, it would naturally squirt out until all the gas in the tank and the tube has exhausted its force. To obviate this I have shaped the tank in such a way that its position can be changed by having several bases to stand on so that when not in operation the fluid will be away from the outlet opening as for instance in the position shown in Fig. 3 and consequently no more fluid can be forced out than what is taken up by the packing or wick *h* when the tank is placed in a nonoperating position.

I do not wish to be confined to the precise construction shown in the drawing, any modification in the construction and shape of the parts may be made if desirable without departing from the scope of my invention. The tank may if desired be made circular in form as shown in Fig. 4.

I claim:

1. A torch comprising a closed fluid containing tank provided with two bases constituting supports for the tank when in upright and inverted position and having an opening, a burner tube connected to said opening, and a packing in said tube to form a wick and regulate the flow of the liquid, said opening being located below the level of the fluid in the tank when the device is

in operating position and above the fluid level when the tank is inverted.

2. A device of the kind described, comprising a fluid containing tank provided with two bases constituting supports for the tank when in upright and inverted position and having an opening, a burner tube extending from the opening, and a wick arranged in said tube to uniformly feed the fluid, said opening being located near the bottom of the tank when the torch is in operating position.

3. A torch comprising a fluid containing tank provided with two bases constituting supports for the tank when in upright and inverted position and having an inlet opening and an outlet opening, a plug fitted in said inlet, a burner tube attached to the outlet, and a wick arranged in the tube to prevent excessive flow of the fluid to the flame when the device is in operating position, said outlet and inlet openings being located, respectively, near the bottom and top of the tank.

4. A torch comprising a fluid containing tank provided with two bases to constitute supports for the tank when in upright and inverted position and having an opening, a burner tube connected to said opening and located near the lower part of the tank, a packing arranged in the tube to form a conductor and feed sufficient fluid to maintain the flame when the device is in operating position, and a wall situated in the tube and having an outlet opening.

5. A torch comprising a fluid containing tank provided with two bases to constitute supports for the tank when in upright and inverted position and provided with an inclined bottom and having an opening located near the lowest part of the inclination, a burner tube extending from the opening, and a packing arranged within the tube adapted to conduct the fluid.

In testimony whereof I have hereunto set my hand in the presence of two subscribing witnesses.

OTTO BARTEL.
